UNITED STATES PATENT OFFICE.

LOUIS E. WOOD, OF FARRELL, PENNSYLVANIA.

OIL AND GREASE GUN.

1,393,001.

Specification of Letters Patent.

Patented Oct. 11, 1921.

Application filed June 4, 1920. Serial No. 386,555.

To all whom it may concern:

Be it known that I, Louis E. Wood, a citizen of the United States, residing at Farrell, in the county of Mercer and State of Pennsylvania, have invented certain new and useful Improvements in Oil and Grease Guns; and I do declare the following to be a full, clear, and exact description of the invention, such as will enable others skilled in the art 10 to which it appertains to make and use the same.

This invention relates to an improved oil and grease gun and one object of the invention is to provide a lubricating gun which 15 can be used for oil or grease and which can be easily adjusted to permit the plunger to be moved through the cylinder by a sliding movement or to be fed longitudinally through the cylinder by a rotary movement 20 after the threads of the plunger have been engaged by thread engaging plates.

Another object of the invention is to provide an improved actuating element for moving the thread engaging plates into and 25 out of an operative position, the actuating element being rotatably mounted and having a turning stem or neck which extends through a cap holding the actuating element in place.

Another object of the invention is to so 30 construct this improved gun that the thread engaging plates and actuating element may be carried by the head closing the end of the cylinder.

This invention is illustrated in the accompanying drawings wherein:

Figure 1 is a view showing the improved gun in side elevation.

Fig. 2 is a sectional view through the 40 upper portion of the gun taken along the line 2-2 of Fig. 1.

Fig. 3 is a transverse sectional view taken along the line 3-3 of Fig. 2.

Fig. 4 is a transverse sectional view taken 45 along the line 4-4 of Fig. 2.

Fig. 5 is a view showing the thread engaging plates in side elevation.

Fig. 6 is a top plan view of the thread 50 engaging plates.

This improved gun is provided with a cylinder or barrel 1 which is open at its upper and lower ends and at its lower end carries a head 2 which forms a discharge nozzle.

The upper end of this barrel is internally

threaded and is closed by a head 7 which is externally threaded and is provided intermediate its length with a collar 8, the collar being milled to permit easy turning of the head and in addition to permitting easy 60 turning of the head limiting movement of the head into the barrel. This head is provided with a passage 9 through which a threaded plunger 10 slidably passes and this passage 9 has its outer end portion enlarged 65 to provide a pocket 11 leading inwardly from the depression of seat 12 formed in the head as shown in Fig. 2. It will thus be seen that since the passage 9 is unthreaded and of greater diameter than the threaded stem 70 or plunger 10 this plunger may be grasped by the handle 13 and moved longitudinally to reciprocate the piston 10' carried thereby for discharging the oil or grease from the barrel.

When discharging heavy grease from the barrel it is desired to have the plunger moved through the barrel at a relatively slow speed and in order to do so there have been provided plates 14 which are slidably mounted in 80 a groove or seat 15 cut transversely in the bottom of the pocket 12 and having arcuate necks 16 which extend into the socket 11 and are internally threaded for engagement with the threads of the plunger. It will thus be 85 seen that when the plates 14 are moved inwardly the threads of the necks 16 will be brought into engagement with the threads of the plunger and it will be necessary to turn the plunger in order to feed the plunger longitudinally of the barrel.

It is desired to permit the plates to be easily and quickly moved to an operative or inoperative position and in order to do so there has been provided a disk 17 which 95 fits into the pocket 12 above the plates 14 and is provided with arcuate slots 18 cut to provide cam slots. Pins 19 extend from the plates 14 into the slots 18 and as the disk is rotated the action of the cam walls 100 upon the pins will cause the plates to be moved into or out of engagement with the plunger according to the direction in which the disk is rotated. This disk is rotatably held in engagement with the head 7 by 105 means of a cap 20 which is screwed upon the threaded upper portion of the head and this cap is provided with a central opening through which extends the neck 21 of the disk, a collar 22 being screwed upon the ex- 110

tended upper portion of the neck and milled so that the disk can be easily rotated. It will thus be seen that with this improved construction the collar 21 may be grasped 5 and the disk thus rotated to move the plates 17 into or out of engagement with the plunger. If the plates are in engagement with the plunger the plunger must be rotated when moving it longitudinally of the valve 10 and therefore heavy grease may be readily forced out of the gun and into a crank casing or gear housing. After the heavy grease has been forced out of the barrel and it is desired to return the plunger to the upper end 15 of the barrel for refilling the disk will be rotated to move the plates outwardly and the plates will then be out of engagement with the plunger and the plunger may be moved longitudinally of the barrel by a direct pull. 20 The barrel can then be refilled with heavy grease and the plates again moved to the operative position or if it is desired to use the gun for oil the plates will be left in in-operative position and the plunger simply 25 pushed inwardly to force the oil through the outlet of the head 2.

What is claimed is:

1. A structure of the character described comprising a threaded shaft, a block having 30 an opening slidably receiving the shaft, the opening having its outer end portion enlarged and the block being cut from its outer face to provide a pocket having a countersunk portion forming a seat extending 35 across the bottom of the pocket about said opening, a cap for said pocket carried by said block, plates slidably mounted in the seat upon opposite sides of the shaft and having internally threaded neck extensions 40 fitting into the enlarged end portion of said opening for engaging the threaded shaft when moved inwardly to an operative position, and operating means for moving the

plates into and out of an operative position including an actuating element extending 45 through the cap.

2. A structure of the character described comprising a threaded shaft, a block having an opening slidably receiving the shaft, the block being cut from its outer face to provide a pocket having a countersunk portion forming a seat extending across the bottom of the pocket and intersected by the opening, latching plates slidably fitting in the seat and having threads for engaging 55 the shaft when moved into an operative position, a disk in said pocket having a neck loosely fitting about said shaft, a cap for said socket having an opening receiving the neck, the disk being provided with arcuate 60 cam slots, and pins extending from said plates through the slots of the disk to impart sliding movement to the plates into and out of operative engagement with the shaft when the disk is rotated through the medium 65 of said neck.

3. A structure of the character described comprising a threaded shaft, a block having an opening slidably receiving said shaft, the block being cut from its outer face to provide a pocket, a cap for said pocket carried by said block and provided with an opening, plates slidably mounted in said pocket for movement into and out of engagement with the threads of the shaft, a disk rotatable 70 in said pocket and provided with a central neck extension fitting loosely about the shaft and extending through the opening of the cap, and means for transmitting sliding 75 movement to the latching plates when said disk is rotated through the medium of neck extension.

In testimony whereof I have hereunto set my hand.

LOUIS E. WOOD.
